(57) **CLAIM**

The ornamental design for a toy water ball as shown and described.

DESCRIPTION

FIG. 1 is a perspective view of the toy water ball in a closed state in accordance with a first embodiment of our new design;

FIG. 2 is another perspective view thereof, showing the toy water ball in an open state;

FIG. 3 is a cross-sectional view thereof, showing the toy water ball in the open state;

FIG. 4 is a perspective view of a toy water ball in a closed state in accordance with a second embodiment of our new design;

FIG. 5 is another perspective view thereof, showing the toy water ball in an open state;

FIG. 6 is a cross-sectional view thereof, showing the toy water ball in the open state;

FIG. 7 is a perspective view of a toy water ball in a closed state in accordance with a third embodiment of our new design;

FIG. 8 is another perspective view thereof, showing the toy water ball in an open state; and,

FIG. 9 is a cross-sectional view thereof, showing the toy water ball in the open state.

The broken lines in the drawings depict portions of the toy water ball that form no part of the claimed design.
